UNITED STATES PATENT OFFICE.

GEORGE L. ANDERS AND THEODORE N. VAIL, OF BOSTON, MASS.

RELAY OR CIRCUIT-CLOSER.

SPECIFICATION forming part of Letters Patent No. 242,408, dated May 31, 1881.

Application filed May 16, 1879.

To all whom it may concern:

Be it known that we, GEORGE L. ANDERS and THEODORE N. VAIL, both of Boston, in the State of Massachusetts, have invented a new and useful Improvement in Relays, of which the following is a specification.

The invention consists in the combination, with a single line-wire and a central station containing a suitable battery and operating-key, of several local circuits and a number of relays corresponding to the number of local circuits, the construction and arrangement of the relays being such that any one of them, and only one of them, can be operated at one time to complete its local circuit according to the intensity or the polarity, or the intensity and polarity, of the current sent over the main line.

The invention also consists in certain details of construction.

It further comprises the use, in connection with one or more instruments causing a signal to be given by steady currents, such as furnished by a battery, of a bell or signal instrument located in the same line-wire and rapidly alternating currents from a magneto-generator.

In the drawings, Figure 1 is a plan of a relay constructed according to our invention. Fig. 2 is a side elevation of the same. Fig. 3 is a plan with upper portions removed. Fig. 4 is a sectional elevation. Figs. 5, 6, 7, and 8 are diagrams illustrating the application of our invention to six local circuits. Fig. 9 is a diagram illustrating a circuit with six stations provided with relays operated by constant currents, and a seventh station provided with a magneto-bell.

Our invention, independently of the peculiar construction of the instrument we use, will be most easily understood by an examination of the diagram shown at Fig. 8, where there is shown a central station with battery and operating-keys, a main line, six relays, and six local bell-circuits. The battery at the central station need not be further described than to say that it has keys by which a positive or negative current may be sent over the line, and keys by which the strength of the full current may be twice diminished.

At each of the six local stations C C repre-

sent two spools of the electro-magnet of the relay, and G represents a polarized armature. To the latter is connected one of the wires, w' , of the local circuit, containing a local battery and bell, as shown, the return-wire w^2 connecting with a contact-screw, P.

At stations 1, 2, 4, and 5 is represented a metallic spring, always pressing against the contact-screw P except when pushed away by the armature G, as will be explained hereinafter. At stations 3 and 6 a similar spring is shown, which must be pressed back by the armature before the latter reaches the contact-screw.

At each station is shown a spring, the force of which is to be overcome before the armature G can establish a contact with the contact-screw P and complete the local circuit. Using letters which are used to represent springs in the instrument, the construction of which will be presently explained, we may anticipate by saying that the springs have the strength of those in the instruments which are lettered the same, viz: at stations 1 and 4 the springs have the strength of springs e and c ; at stations 2, 3, 5, and 6, of e and c and o .

The poles of the polarized armature at stations 4, 5, and 6 are the reverse of the poles at stations 1, 2, and 3. It is therefore obvious that a current which will move, or tend to move, the armature G at stations 1, 2, and 3 to bring it in metallic contact with screw P will have no effect at the other three stations, and therefore the current which must be used for stations 4, 5, and 6 will have no effect at stations 1, 2, and 3. Now, by construction the force of the spring e at stations 1 and 4 is such that when the current is in the proper direction it will be overcome, so that contact is made by the armature G with spring e , thus making metallic contact with screw P, when both cut-out keys of the main battery are used and a current of very little strength is sent over the main line; but if only one or neither cut-out key is used, and a current of greater force is sent over the main line, the armature G will strike against the spring e with such force as to push that spring away from screw P and insure a break in the local circuit. In like manner, by construction the coiled spring e of stations 2 and 5 will be overcome and con-

tact made between armature G and spring o, and the local circuit established, when one cut-out key only is used; but if no cut-out key is used the current will be so strong that the spring o will be pushed away from screw P and a break in the local circuit insured; and by construction this strong current will overcome the springs e c and o at stations 3 and 6, and make contact with P.

- 10 From this description it follows that each local circuit may be established by sending over the main line a current of suitable intensity and polarity; but this is not all. It follows equally that if a current is set over the main 15 line of suitable intensity and polarity to cause the completion of any one of the local circuits, that current will establish breaks in all five of the other local circuits. A bell can therefore be rung at any one of the six stations by an 20 operator at the central station, but cannot possibly be rung at any two of them at the same time.

The diagram Fig. 8 to which the foregoing description relates is intended mainly to illustrate the operation of a series of six relays in accordance with the invention, and in it, for the purpose of more simple illustration, the relays are shown with a single armature, it being obvious that a polarized armature, in addition to the attraction and movement depending on the polarization, may, like a soft-iron armature, be made to overcome a regulated spring-pressure according to the strength of the magnet. In practice we employ two armatures, one polarized, so that the relays will bring in their local circuits only under the action of currents of one polarity, and the other a neutral armature for overcoming the tension of springs e o. When there are only two relays 35 on the same circuit, or even where there are four, two of each polarity, one armature polarized may be used with good effect in each relay. It is obvious, also, that if the relays at stations 1, 2, and 3 only were used there would 40 be no need of employing a polarized armature.

To a line having six stations provided with relays, as just described, a seventh station may be added by providing a magneto-bell, which may be rung by a magneto-generator at the central office independently of the vibrating bells at the other six stations. It is obvious that a magneto-bell of this character could be used to give a signal at its own station independent of the others on a circuit connected with instruments operated by constant currents, when the number of said instruments is less than six. Fig. 9 is a diagram showing the six relays, as represented in Fig. 8, without their local circuits, and a seventh station provided with a 50 magneto-bell. The bell is represented by Z.

Having now described the nature and mode of operation of our invention, we proceed to describe in detail the construction of the relay used at the local stations, premising the description, however, by saying that while we claim some of the details of construction as our

invention, the principal feature of our invention can be worked out independently of the precise details represented and described.

A is a wooden bed; B, a brass frame; C, an 70 electro-magnet supported by the frame B.

D is a soft-iron armature, attached to one end of a vibrating brass rod, E, which is rigidly secured at its center to a rock-shaft, F, whose ends have bearings in the inner ends of 75 two adjusting-screws, a a, in the upper part of the frame B.

Projecting downward from the rock-shaft F is a rod, b, whose lower end is attached to a spring, c, the tension of which is regulated by 80 the adjusting-screw d, as shown. The force of the spring c tends to lift the soft-iron armature D from the electro-magnet.

G is a polarized armature swinging on a post, H, which is insulated from the frame by a 85 plate, r.

A spring, e, secured to the polarized armature, and pressing against one of the spools of the magnet, exerts its force against a current sent through the electro-magnet in one direction, as hereinafter explained.

J is a metallic post secured to the frame B. It supports a piece of insulating material, K, whose office is to give support to four pieces of metal—viz., an elbow-piece, m, a pin, n, a 95 bent spring, o, and an elbow-piece, p. Of these four pieces the pin n and bent spring o are at times in contact with each other, otherwise the four parts are insulated from each other.

The upper arm of the elbow-piece m supports an end of the rod E when the soft-iron armature is not attracted to the electro-magnet. Through the other arm of the elbow-piece m is an adjusting-screw, j, in contact with the inner end of which the nearer end of the polarized armature is brought to close, or assist in closing, a branch circuit, as will be herein-after described. In like manner the upper arm of the elbow-piece p has an adjusting-screw, l, against the lower end of which the rod E is 110 at times lifted.

S' are screw-cups connecting with the line, and O O' are the screw-cups connecting with the branch circuit.

A light current sent through the electro-magnet has no effect upon the soft-iron armature, and does not disturb the contact between the end of the rod E and the elbow-piece m. A current of any strength, however, if in a proper direction, will cause the polarized armature to overcome the force of the spring e and bring the polarized armature into contact with the adjusting-screw j. A wire, w', connects the screw-cup O with the post H, and a second wire, w'', connects the screw-cup O' with the frame B, say, at adjusting-screw a. This is the condition at stations 1 and 4, the two stations differing only in the polarity of the armature G, and the bell rings when the polarized armature swings against screw j, the local circuit being then completed, and being, as before stated, from screw-cup O, by wire w', to

post H, through that post to the polarized armature G, then to adjusting-screw j, elbow-piece m, rod E, rock-shaft F, frame B, by wire w², to screw-cup O'. (See Fig. 5.)

5 At stations 2 and 5 the screw-cup O is connected with post H by wire w', but the wire w² from screw-cup O' is attached to the pin n; and to ring the bell at stations 2 and 5 a current of medium strength is sent through 10 the electro-magnet, sufficient to lift the rod E from the elbow-piece and bring it into contact with bent spring o, but not of sufficient strength to lift the bent spring o from contact with pin n. A third wire, w³, also connects elbow-piece 15 m with the vibrating rod E, and whenever the current through the electro-magnet brings the polarized armature into contact with the screw j the bell rings, the bell-circuit being from screw-cup O, by wire, to post H, and through 20 post H to polarized armature G, thence to screw j, elbow-piece m, by wire w³, to vibrating rod E, bent spring o, pin n, by wire w², to screw-cup O'. (See Fig. 6.)

At stations 3 and 6 screw-cup O is still connected with post H, but screw-cup O' is connected with elbow-piece p, the additional wire, w⁴, in this instance connecting the elbow-piece m with the spring o, and the current has sufficient strength to cause the rod to strike the 25 adjusting-screw l, and at the same time to lift the spring o from the pin n. The bell is rung when the polarized armature G strikes the adjusting-screw j, the local circuit being then completed as follows: from screw-cup O, by 30 wire w', to post H, polarized armature G, thence to screw j, elbow-piece m, by wire to w⁴, to spring o, rod E, adjusting-screw l, elbow-piece p, by wire w² to cup O'. (See Fig. 7.)

It is obvious that the spring o, pin n, and 40 elbow-piece p may be removed from the instrument used at stations 1 and 4, and that the elbow-piece p may be removed at stations 2 and 5. At whatever station used the instrument shown requires the wires w' and w². The instrument used at stations 2 and 5 requires an additional wire, w³, and the instrument used at the stations 3 and 6 requires the additional wire w⁴. The wires are shown in the diagrams 45 5, 6, and 7.

50 Referring again to Fig. 8 it is obvious that stations 3 and 6, or that stations 2, 3, 5, and 6 might be omitted without departing from the principle of our invention.

We are familiar with the construction and 55 operation of relays in use in systems of multiple telegraphy, and make no claim to such construction and mode of operation. Such systems resemble our invention in making use of a single line-wire over which are sent currents 60 of different intensity and different polarity, but here the resemblance ceases. In those systems it is provided that several local circuits

and their respective instruments may be operated simultaneously, which provision must be guarded against, for it is no less essential in 65 our system that an operator shall not be able to ring more than one bell at a time than it is that he shall be able to ring any one bell at will.

We claim—

1. A main electric circuit, in combination with a series of local circuits, and a series of relays constructed substantially as described, whereby any one of said relays, but only one at a time, may be operated to bring in the local 75 circuit, the currents for operating the several relays differing from each other in intensity or polarity or intensity and polarity, as set forth.

2. In an electric circuit, a series of relays, 80 part of one and part of the opposite polarity, the relays of the same polarity being adapted to connect in a local or branch circuit by the action of currents of different intensity, substantially as described.

3. The polarized armature G and the vibrating arm E, provided with the soft-iron armature D, in combination with the electro-magnet C, the arm m, screw j, and wires w' and w², substantially as described, for the purpose 90 specified.

4. The polarized armature G and the vibrating arm E, provided with the soft-iron armature D, in combination with the electro-magnet C, the arm m, screw j, spring o, pin n, and 95 wires w', w², and w³, substantially as described.

5. The polarized armature G and vibrating arm E, provided with the soft-iron armature D, in combination with the electro-magnet C, arm m, screw j, spring o, screw l in metallic 100 connection with wire w², and the wires w' and w⁴, substantially as described, for the purpose specified.

6. The combination, with instruments for 105 causing signals to be given at one or more stations on the line and operated by constant currents, of a magneto bell or signal placed on the same line-wire and operated by the rapidly-alternating currents of a magneto-generator for giving a signal independent of afore- 110 said instruments.

7. In a telephone signal apparatus, a series 115 of relays comprising each a neutral and a polarized armature and contact-points as indicated, the neutral armatures being adjusted differently, and the polarized armatures being of unlike polarity in different instruments, substantially as described.

GEORGE LEE ANDERS.
